PLASTIC BAG

Richard H. Wilke, Atlanta, Ga.

Application May 13, 1953, Serial No. 354,678

3 Claims. (Cl. 150—1)

This invention relates to plastic bags, and more particularly to strong, thin filmed reinforced bags made of plastic or synthetic rubber-like sheet material.

Bags for flour, feed, seed, meat, chemicals, vegetable products, mineral products, and the like, have heretofore been made of paper, fabric, a combination of plastic and fabric, a combination of paper and fabric, and the like, but such prior art structures have not been found completely satisfactory. For example, the prior art paper bags when wet have had a tendency to tear or separate along their seams while the woven fabric bags have not had sufficiently close weave to insure that finely ground material contained therein will not sift out. Further, the prior art bags made of heat sealable material such as rubber hydrochloride and polyethylene, like the paper bag, have had a tremendous tendency to tear when containing heavy material. Other prior art bag structures have been found to be expensive to manufacture or complicated in structure.

Accordingly, it is an object of my invention to provide a plastic bag which will overcome the disadvantages attributed to the prior art bags, and which has a maximum tensile strength so that it does not tear easily.

Another object of my invention is to provide a plastic bag having extreme thinness and being reinforced in such a way that it is substantially impossible to tear under normal stress and strain conditions.

Another object of my invention is to provide a strong plastic bag of thin, reinforced plastic sheet material which is capable of being coated with insecticidal chemicals on the outside thereof with no danger of these chemicals penetrating within.

Another object of my invention is to provide a plastic, multi-ply bag having maximum tensile strength, good insulating qualities, and being so constructed that it will avoid the normal sweating characteristics of the prior art bags.

Other and further objects and advantages of my invention will become apparent from the following description when taken in conjunction with the accompanying drawings in which like characters of reference designate corresponding parts throughout the several views, and wherein:

Fig. 1 is a plan view of a blank from which a bag made in accordance with my invention is constructed.

Fig. 2 is a front elevation of a bag constructed from the blank shown in Fig. 1.

Fig. 3 is an enlarged fragmentary view of a detail.

Fig. 4 is a cross-sectional view taken along line 4—4 in Fig. 2.

Fig. 5 is a fragmentary top view of the detail shown in Fig. 3.

Fig. 6 is a plan view of one of the blanks from which a multi-ply bag is made according to my invention.

Fig. 7 is a front elevation of the multi-ply bag made according to my invention utilizing two blanks such as the one shown in Fig. 6.

2

Fig. 8 is a cross-sectional view taken along line 8—8 in Fig. 7.

In the embodiments of my invention chosen for purpose of illustration, Fig. 1 shows a blank of thin sheet material which may be made of plastic or synthetic rubber material, cellophane, regenerated cellulose, cellulose acetate, cellulose acetate butyrate, cellulose nitrate, ethyl cellulose, or any such cellulose derivatives, as well as products obtained by the polymerization of vinyl compounds and other plastic materials used in the plastic and synthetic rubber industry to make thin plastic or plastic-like films. As shown in Fig. 1, this blank has a smooth substantially rectangular border portion 10 around the outside, and the central or interior portion of the blank is formed of a thin continuous sheet 11 which is criss-crossed by intersecting reinforcing ribs, the vertical ribs being denoted by numeral 12 and the laterally disposed ribs by numeral 13. Vertical ribs 12 extend continuously between opposite horizontal portions of border portion 10 while horizontal ribs 13 extend continuously between opposite vertical portions of border portion. It will thus be seen that the blank from which my bag is made is economical in the use of material because the material which would otherwise form a thickness equal to the thickness of the border portions is forced up into the ribs which criss-cross and provide adequate protection for the thin sheet 11, so as to prevent tearing thereof.

The reinforced blank of thin plastic sheet material from which my bag is made, may be formed by casting, extruding, calendering on engraved surfaces, or by other methods known in the plastic and synthetic rubber industry for making thin films of sheet material and the like.

As shown in Fig. 2, the blank of Fig. 1 is folded upon itself in a manner customary in the bag-making art, and the opposite smooth vertical edges of border portion 10 are fastened together by glueing, heat sealing or other processes known in the bag-making art to form a cylinder. Thereafter, one horizontal edge portion of border portion 10 is sealed against itself while the other horizontal portion is left open to receive the contents, after which it is sealed as described before.

Fig. 4 is a cross-sectional view showing the completed envelope of the bag with the smooth border portions of the blank overlapping and fastened together. From this view, it will be noted that the exterior wall of the bag is substantially smooth, whereas the inner wall of the bag is provided with reinforcing ribs 12 and 13. From Fig. 4, it will be noted that the thin sheet 11 which is integral with the border portion 10 presents a smooth outer surface which readily lends itself to printing thereon of information regarding the contents of the bag or other ornamentation.

A modified form of my thin film plastic bag is shown in Figs. 6, 7 and 8, this modification being a multi-ply bag using two of the blanks shown in Fig. 1. These blanks are fitted together and form a border 14 within which are disposed parallel thin sheets 15, 15' which are spaced apart by inwardly projecting criss-crossed intersecting ribs 16, 16', which are respectively integral therewith. These criss-crossed ribs are substantially identical with the intersecting ribs 12 and 13; however, each of the ribs 16 is joined to its respective complementary rib 16' by heat sealing, glueing or other process common in the bag-making art. It may thus be seen from Fig. 8 that ribs 16, 16' and thin films 15, 15' define a plurality of separated dead air spaces 17 which form excellent insulating areas.

As described for the formation of the bag by use of a single blank, the blank shown in Fig. 6 is folded upon itself in a manner customary in the bag art; however, the smooth edges or border portions 14 are joined to their respective border portions as illustrated in Fig. 8 and are respectively fastened together by glueing, heat sealing or

other process common in the bag-making art to form a vertical seal along the bag as shown in Fig. 8. On the other hand, the upper and lower border portions of the bag are merely sealed in a manner similar to the sealing of the bag illustrated in Figs. 2 and 4.

It is to be noted that when forming a bag as a container for material such as flour, it may be found desirable to select a material, from the materials mentioned above, which will allow limited "breathing" or osmotic air changes within the bag and yet prevent the flour from sifting out. Thus, a thin cellophane would probably be selected since it provides a web having sufficient texture to prevent the flour from sifting out while being limitedly porous to allow the "breathing" described above. On the other hand, a rubber hydrochloride or polyethylene bag would be used where the material contained therein did not require osmotic air changes, and the bag, thus formed, could be sprayed with most insecticides without deleterious effects.

It will be obvious to those skilled in the art that, by use of the structure herein disclosed and the proper selection of plastic or plastic-like materials, the inherent properties of the bag may be changed to fit requirements of the materials which it is to contain. It will be equally obvious that other changes may be made in the embodiments selected for illustration without departing from the scope of my invention as defined by the appended claims.

I claim:

1. In an imperforate bag, a wall made of plastic sheet material, said sheet material having a substantially rectangular smooth, relatively thick border portion and an

interior portion, said interior portion comprising a relatively thin continuous sheet joined to said border portion, said border portion extending around said interior portion and defining opposite portions and an upper portion and a bottom portion, and intersecting reinforcing ribs integrally connected to said sheet and criss-crossed across the surface of said sheet, certain ribs joining said opposite portions of said border portion and forming with said continuous sheet a thickness substantially equal to the thickness of said border portion.

2. The structure defined in claim 1 wherein said opposite portions of said border portion are joined to form a cylinder and said bottom portion of said border portion is sealed against itself.

3. The structure defined in claim 1 including a second plastic wall joined to said first mentioned wall and defining with said relatively thin continuous sheet of said first mentioned wall and said intersecting ribs a plurality of closed air spaces.
